CLAIM

The ornamental design for an electronics head, as shown and described.

DESCRIPTION

FIG. 1 is a perspective view of one embodiment of a new design of an electronics head shown on a fuel dispenser; FIG. 2 is front view of the electronics head of FIG. 1, the back view being a mirror image thereof; FIG. 3 is a left view of the electronics head of FIG. 1; FIG. 4 is a right view of the electronics head of FIG. 1; FIG. 5 is a top view of the electronics head of FIG. 1; and, FIG. 6 is a bottom view of the electronics head of FIG. 1. The broken lines in the drawings form no part of the claimed design.
